SLIDER FOR SEPARABLE FASTENERS

Louis H. Morin, Bronx, N.Y.

Application January 22, 1953, Serial No. 332,634

3 Claims. (Cl. 24—205.14)

The present invention relates to new and novel improvements in a slider for a separable fastener and relates more particularly to an improved construction of a slider and pull.

An object of the present invention is to provide a slider and a pull which can be assembled in a simple and inexpensive manner. Another object of the invention is to provide a slider and pull that can be assembled as a unit simultaneously by the attachment of the slider to a pair of separable fastener stringers.

A further object of the present invention is to provide a slider and pull of this character having an automatic spring actuated lock element.

Other novel features of the invention will be best understood from the following description, when taken together with the accompanying drawing, in which certain embodiments of the invention are disclosed and, in which, the separate parts are designated by suitable reference characters in each of the views and, in which:

Fig. 1 is a plan view of one form of a slider pull assemblage which I employ with part of the construction broken away and in section.

Fig. 2 is a longitudinal sectional view through the structure, as shown in Fig. 1.

Fig. 3 is a view similar to Fig. 1 of a modified form of construction, with part of the pull broken away; and

Fig. 4 is a longitudinal sectional view through the structure shown in Fig. 3.

In Figs. 1 and 2 of the drawing, I have shown a slider body 10 having top and bottom walls 11 and 12 joined by a connecting web 13 at the double channel end portion 14 of the body. The other single channel end portion 15 of the body has inwardly extending flanges 16 and 17 on the walls 11 and 12, respectively.

The end portion 15 is considerably narrower than the central portion 18 of the body, thus producing what may be termed recessed sides 19, in which side members 20 of a pull 21 are free to operate. The side members 20 are within boundaries of the central wide portion 18 of the slider body, as clearly illustrated in Fig. 1 of the drawing.

The pull 21 has a solid axle or pivot bar 22 which extends through the body of the slider and integrally joins the sides 20 of the pull in rounded portions 23. The sides 20 of the pull may be united in a contracted or rounded end 24. Such a pull may be formed in one piece by diecasting or the like.

The inner surface of the top wall 11 of the slider is provided with a bearing recess 27 which extends transversely of the slider and receives the pivot bar or axle 22 of the pull therein. The pivot bar 22 of the pull carries a projecting locking element 25 which extends between adjacent scoops on the stringer when the pull is in the position illustrated so as to lock the slider in place on the stringer.

An enlarged recess 26 is provided at one end of the bearing recess 27 to receive the locking element 25 when the pull is raised and the lock element is disengaged from

the scoops to move the slider along the stringers. The slider may also be provided with an enlarged recess 26' at the opposite side of the wall 11 to facilitate the use of an additional lock element, similar to the element 25, if desired. However, the single element is shown in the present construction.

The slider body 10 is preferably diecast and the distance between the opposing faces of the flanges 16 and 17 is sufficient to permit the pivot bar or axle to pass between them in assembling the pull to the slider. After the pull has been put in place in the slider body, the distance between the flanges 16 and 17 is then reduced by compressing the slider body so that the pivot bar 22 can no longer pass between them. If desired, the slider and pull may be assembled at the same time as the slider is attached to the stringers of a separable fastener. The method of attaching sliders and pulls to separable fastener stringers in this manner is more fully described and claimed in my copending application Serial No. 295,244 filed June 24, 1952, for Method of Assembling Sliders With Separable Fastener Stringers and in my application Serial No. 332,633, filed January 22, 1953, filed concurrently herewith for Method of Assembling Sliders With Pulls and With Separable Fastener Stringers to which reference may be made.

When the slider 10 and the pull 29 have been assembled and have been attached to a separable fastener stringer, the pivot bar 22 of the pull will rest on the tops of the scoops or elements on the stringers, as indicated by the dotted lines in Fig. 2, and will be held in the bearing recess 27 in the slider thereby. This is made possible by the fact that the pivot bar 22 extends through the slider body and eliminates the need for separate means to secure the pivot bar in the bearing recess.

In Figs. 3 and 4 of the drawings, I have shown at 28 a modified form of slider body, having top and bottom walls 29 and 30 joined by a connecting web 31. At 32 and 33 are shown inwardly extended flanges, generally similar to the flanges 16 and 17. It will also be apparent that the general contour of the slider body 28 is the same as that illustrated in Fig. 1, in other words, includes the recessed sides 34, providing the clearance for the side members 35 of a pull 36. The pull 36 has a pivot bar 37 which extends transversely across the slider body 28 and is movably supported in an angularly arranged bearing recess 38 in the inner face of the top wall 29 of the slider body. The recess 38 opens into the channel of the slider body and through the flanges 32, as seen at 39 in Fig. 4 of the drawing, to permit assemblage of the pull, as described above.

The top wall 29 of the slider body has a longitudinal recess 40 in which is arranged an elongated lock element 41 pivoted to the wall 29 by a pivot pin 42, the ends of which are shaped to conform to the contour of the wall 29, as will be apparent.

The element 41 has a downwardly and inwardly extending contracted scoop engaging part 43 which operates in an aperture 44 in the wall 29, which again opens into the channel of the slider body so that the part 43 can engage the scoops of a stringer in retaining the slider against movement thereon. The inwardly extending part 43 of the lock element includes an outwardly extending stop member 45 which engages a cross-bar 46 at the contracted end of the slider. This end of the slider has an aperture or opening 47 which opens into the aperture 44, as will clearly appear from a consideration of Fig. 4 of the drawing. The element 41 is normally held in its operative position, as shown in Fig. 4, by a coil spring 48 arranged in an aperture 49 in the web portion 31 of the slider body, the aperture opening through the top wall 29 and the spring engages an inwardly extending nub or bead 50 on the inner surface

51 of the element 41 arranged directly above the aperture 49. The surface 51 is spaced sufficiently from the top wall 29 of the slider body to provide movement of the lock part 43 of the element out of engagement with the stringer scoops. The element 41 is moved into this inoperative position by movement of the pivot bar 37 of the pull from the position shown in Fig. 4 to the outer extremity of the offset recess 38, as will clearly appear from a consideration of Fig. 4 of the drawing. This last operation is automatic in operation of the slider along the stringers through the medium of the pull, as in other devices of this type and kind.

With both forms of construction, it will appear that the pull is assembled within the recessed portion of the slider body and is free to move in the slider body, but is retained against displacement therefrom by reason of the fact that the pivot bar 22 or 37 is greater in diameter than the clearance between the flanges 16 and 17 or 32 and 33, respectively. This construction provides a very simple and, yet, strong and durable coupling of the pull with the slider body and the assemblage may be accomplished by merely compressing the slider body as previously described.

With the structure shown in Figs. 3 and 4, it will be understood that the lock element 41 is first attached to the top wall 29 of the slider body before assemblage of the fingerpiece or pull and, by keeping the element 41 within boundaries of the top wall, pressure can be applied to the wall in the assemblage above referred to. It is preferred that the element 41 has a rounded portion 52 on its inner surface, seating upon a slightly rounded surface 53 on the wall 29, so as to facilitate the free swinging movement of the element 41, while at the same time giving strength to this element at the pivot portion thereof.

Having fully described my invention, what I claim as new and desire to secure by Letters Patent is:

1. A slider comprising a channelled body defined by spaced top and bottom walls joined at one end by a connecting web, the top wall having a transverse recess of elongated cross-section tunneling therethrough and opening through the inner surface and sides of said wall, a pull having a pivot bar located in said transverse recess, the cross-sectional size of the pivot bar being greater than the distance between said spaced walls so that removal of the pull through said space is prevented, said top wall having a longitudinal recess opening through the upper surface thereof and intersecting said transverse recess, a spring-biased lock element comprising an elongated bar set in the longitudinal recess so that the upper surfaces of said wall and lock element, when the latter are viewed in cross-section, present a smooth contour, means pivoting the lock element to said wall, and said lock element being engageable by the pivot bar.

2. A slider comprising a channelled body defined by spaced top and bottom flanged walls, said walls being joined at one end by a connecting web, one of said walls having a transverse recess in the lower surface thereof with openings in the sides of said wall, said recess when viewed in cross-section extending angularly in said wall, a pull having a pivot bar located in said recess,

5 said pivot bar being solid and extending transversely through the slider body, said recess having a free opening through said lower surface of said wall of a size sufficient to pass the pivot bar therethrough, said pivot bar being larger in cross-section than the space between the flanges of said flanged walls so that removal of the pivot bar through said space is prevented, said pivot bar normally resting on stringer scoops disposed in said slider and being retained in said recess by engagement with said scoops, a spring-actuated locking element carried by said recessed wall, said locking element having an operating portion extending into the angular recess in said wall, and said operating portion being engageable by the pivot bar of the pull.

15 3. A slider for slide fastener stringers comprising top and bottom spaced flanged walls connected by a web at one end portion and having an opposite narrow end portion, a transverse groove in the top wall opening through the lower surface and extending through the flanges thereof, said groove being disposed in the narrow end portion of the slider, the upper surface of said top wall being smooth and free of projections conventionally employed to attach a pull thereto, a pull on said slider comprising a pair of arms connected by a transverse pivot bar, said bar being rotatably disposed in the transverse groove, said opening of the groove in said lower surface of the top wall being free and being of such size as to pass the pivot bar therethrough, the cross-sectional dimension of the pivot bar being greater than the distance 20 between opposed upper and lower flanges of said walls so that removal of the bar through the space between said opposed flanges is prevented, said bar, when the pull is not in use, being adapted to normally rest on stringer scoops disposed in said slider with the scoops serving to prevent the bar from moving out of said groove, the length of the bar plus the width of both arms being not larger than the largest width of the slider, said top wall having a longitudinally extending recess opening through the upper surface thereof and intersecting said transverse groove, an elongated, spring-biased, movable lock element pivotally disposed in said recess, and said pivot bar being movable in said groove so as to engage and move the lock element about the pivot thereof.
